UNITED STATES PATENT OFFICE.

JULIUS M. ALTER, OF BROOKLYN, NEW YORK.

MATCH BOOK AND METHOD OF MAKING.

Application filed April 15, 1926. Serial No. 103,982.

This invention relates to match books and methods of making the same.

Among the objects of this invention is to provide a match book of novel and simplified construction, and one which can be utilized with the maximum ease and facility.

Another object of this invention is to provide a novel method of making matches and match books, wherein the same can be formed of an integral strip of material and at a greatly reduced cost.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof, reference is had to the accompanying drawings in which like reference characters designate the same parts in the several views, and in which—

Figure 1 is a view of a blank having its surface suitably treated according to the first steps of the process.

Fig. 2 is a view of an opposite side of the blank.

Fig. 3 is a perspective view on an enlarged scale showing the folds in the blank.

Fig. 4 is an enlarged perspective view of the completed match book with parts in section.

Fig. 5 is a fragmentary perspective view showing a modified construction of the matches.

Referring now more specifically to the drawings, I show my invention as being formed of a strip of pliable or fibrous material such as paper, the strip assuming the form of a blank 10 which has had one or more of its surfaces suitably treated while constituting part of a large strip or roll of paper of any feasible length and width.

More specifically, the blank 10 out of which I construct my match book has suitable printed matter or advertisements 11 and 11^a formed thereon at that portion of the blank which is to constitute the cover of the book, the advertisements being intended for the outside of the cover. Fold lines 12 and 13 are provided between the panels 11 and 11^a to provide a neat end or top for the cover. Friction material F extends across the blank adjacent to a panel 14 and on the same side of the blank as the printed matter. Fold lines 15 and 16 are provided on the blank

at the side margins of the ignition means F on panel 14. A fold line 17 extends across the blank in spaced relation to the line 16 to provide a spacing portion or member. 60 The remaining portion of the blank is utilized largely to form a pair of rows of matches to be retained in the book cover. More specifically, three fold lines 18, 19, and 20 are provided in uniformly spaced relation to each other and extending transversely of the blank. A plastic ignition material is arranged along fold lines 18 and 20 in the form of the bands 18^a and 20^a on the same side of the blank as the printed matter 70 and frictional material aforesaid. Slits 21 are formed in the blank extending transversely through fold lines 18 and 20. The slits are uniformly spaced from each other across the blank to provide in the finished 75 product matches of equal size, and extend to equal distances from their respective fold lines 18 and 20 upon opposite sides of said fold lines. The ends of the slits preferably terminate in the blank and in spaced relation to fold lines 17 and 19. While the distances between lines 18, 19, and 19, 20 are equal, the distance between lines 17, 18 is less for a purpose to be disclosed herein- 80 after, and equal substantially to the distance 85 between line 20 and the end 22 of the blank. The reverse side of the blank is coated with glue from the end 22 of the blank preferably continuously to a line 23 of the blank be- 90 tween lines 13 and 15 and adjacent to the latter line. It will be understood that as thus far practised, the precise method or order of steps used may be varied in any suitable manner within the scope of this invention, and that, generally, it can be practised in connection with a roll of paper of 95 considerable size which can then be severed into blanks such as indicated in the drawings.

The direction of the various folds can be 100 readily understood by reference to Fig. 3. Fold lines 15 to 20 form a plurality of loops or folds which are similarly directed, lines 16, 18, and 20 forming the tops of the folds, while lines 15, 17, 19 and 22 form the ends 105 or bottoms of the folds. Thus three folds can be made which are disposed to lie side by side. That portion of the blank extending from line 15 to the opposite end of the blank constitutes a reversely directed fold or cover 110 disposed to extend around the matches and with the free end forming a tongue T where-

by the book can be closed. By pressing together the appropriate parts, the glue is rendered effective to provide the completed match book. Thus a pair of rows of matches 5 M having the usual ignition tips is formed. Each of these matches is formed of at least two plies of paper suitably glued together for the sake of stiffness. A match is readily removed as by being torn out of the book 10 in the usual manner according to the construction of match books in common use. A locking hook is provided at 16 which is upwardly disposed in the direction of the matches and adjacent to a row thereof to engage 15 the tongue of the book when the book is closed, the plies of the hook being glued together. The friction surface or part F is at the base of the book about the outside thereof and in its usual place adjacent to the hook. 20 One of the rows of matches is secured to the front page of the cover, and the other to the rear part thereof, thus causing the rows of matches to readily and automatically separate from each other when the book is 25 opened up, rendering the individual matches more accessible to the fingers of the user. More specifically, the front or outer row of matches is secured by glue to the friction part of the cover, while the rear or inner 30 row of matches is secured to the rear part of the cover as between lines 15 and 23. The construction is very simple and the method whereby the match book is produced is especially adapted for quantity production 35 on a large scale, and at the lowest possible cost. The tips of the matches can be formed at such stage of the process as will be found most feasible, the process lending itself readily to any adaptation or use within 40 the scope of the invention.

In course of constructing the matches, the same may be formed of such cross section as taught by the mechanical arts for securing the maximum strength or stiffness in the 45 matches. More specifically, the matches may be formed with a hollow extending therealong, or the cross section of the matches may be of channel or angular form. This result is especially feasible since the matches 50 M are made of pliable material. Specifically, I form a crease or bend 24 extending along each match as by applying pressure to concave the match. This can be done at such stage of the process as is found convenient. 55

In order to permit the rows of matches to nest as closely together as possible, or more specifically, to eliminate the excessive thickness of the match book which is caused by 60 the fact that the heads of the matches in different rows contact or abut against each other when the match book is closed, I may arrange that one row of matches be of a different length from the other row, thus positioning the heads in one row of matches

above the heads in the other row. The heads of the matches, which are the thickest parts thereof, will therefore be out of abutment relation with each other. This result is readily accomplished as by suitably proportioning the various parts in the blank 10. Preferably the front or outer row of matches is made shorter than the inner row, and therefore the distance between lines 18 and 19 in the blank will be less than that between 75 lines 19 and 21. Similarly the distance between lines 17 and 18 will be less than the distance between lines 20 and edge 22.

I claim:

1. A match book formed of a strip of 80 pliable material arranged to provide a plurality of folds, certain of said folds being brought and secured together and slitted to provide a series of matches side by side, others of the folds constituting a cover to inclose the matches.

2. A match book having a cover including a tongue to close the book, a hook member co-operating with the tongue for holding the same in closed position, and a plurality of rows of matches in the book, one row whereof is secured to the front part of the cover adjacent to said hook, and the other row to the rear part of the cover, both rows of matches being secured to the cover at the bottom thereof thus permitting the rows of matches to be separated from each other and from the cover when the book is opened.

3. A match book having a cover including a tongue, a hook co-operating to engage the tongue to render the latter effective to close the book, and matches in said cover formed of integral construction with the cover at said hook and inward of the book.

4. The method of making a match book comprising treating the surface of a strip of material according to the final printed indicia desired thereon and applying adhesive to the opposite sides of the strip, then forming a plurality of folds in said strip, pressing the sides of one of said folds together to render the adhesive effective to constitute the fold about a row of matches, another of said folds at a side of the row of matches and remote from the ignition ends thereof to form a locking hook, and extending another of said folds around the row of matches from said book to form a cover and with the free end of the cover to constitute a tongue to engage with said hook to close the book, the printed indicia being then upon the outside of the cover.

5. The method as set forth in claim 4 wherein a plurality of rows of matches are formed of corresponding folds by gluing the sides of each fold together, and gluing one of said rows to the front part of the cover at said hook and the other row to the rear part of the cover.

6. The method of making a match book in-

cluding the bending of a strip of material to form three folds similarly directed, the first adjacent two of which are of the same size to form rows of matches, while the 5 third is of relatively reduced size to form a locking hook, and a fourth fold in reverse direction with respect to the folds aforesaid so as to form a cover extending around the 10 matches and into engagement with the hook to close the book.

7. The method of making a match book including the bending of a strip of material to form a plurality of similarly directed 15 folds disposed side by side, one of said folds being smaller than the other to provide a locking hook, and the larger fold providing a row of matches, and forming a reverse fold

from said hook to extend around the larger of the two folds aforesaid and engage the hook to close the book. 20

8. A match book formed of an integral blank having a fold, the sides whereof are glued together and slitted to provide a row of matches.

9. A match book of one strip of pliable material having a cover and a row of matches therein and integral therewith, said row of matches being coextensive in width with the cover and formed by uniting a plurality of plies of said strip remote from the 30 ignition points of the matches to increase the stiffness of the book and matches.

In testimony whereof I affix my signature.
JULIUS M. ALTER.
